UNITED STATES PATENT OFFICE.

MATTHEW E. DUNLAP, OF MADISON, WISCONSIN, ASSIGNOR TO UNITED STATES OF AMERICA.

SHRAPNEL PLUG.

Application filed November 5, 1918. Serial No. 261,208.

To all whom it may concern:

Be it known that I, MATTHEW E. DUNLAP, a citizen of the United States, residing at Madison, in the county of Dane and State of Wisconsin, have invented certain new and useful Improvements in Shrapnel Plugs, of which the following is a specification.

My invention relates to plugs for shrapnel shells and the object of my invention is to provide a plug satisfactory for this use constructed of wood. The use of wood for such a plug is extremely desirable in that wood is inexpensive and also is easily worked. Heretofore, however, so far as I know, no wooden plug has been produced which was so constructed that it would not bind in the opening upon being exposed to moisture. Such binding will hamper the removal of the plugs and in many cases the plugs swell to such a degree as to render impossible the removal thereof without injury to the shell. My plug is designed to completely close the opening in the shell and yet is so constructed that exposure to moisture and the swelling consequent thereto will cause no appreciable binding of the plug in the opening.

I have designed two types of plug which fulfill the objects of my invention. I have shown one type in Figures 1 and 2, Figure 1 being a top plan view of my plug and Figure 2 a central vertical section. The other form of plug which I have designed is illustrated in Figures 3, 4, and 5, wherein Figure 3 represents a top plan view of the plug, Figure 4 a central vertical section along the line 4—4 of Figure 3, and Figure 5 a section at right angles to the section of Figure 4 and along the line 5—5 of Figure 3.

Referring to Figures 1 and 2 for a description of the first form of plug, 1 represents a cylindrical annular body provided on its exterior surface with threads 2. This body 1 is shouldered at 3 to merge into a neck part 4 which is hollowed at its lower side as a continuation of the opening in the body 1 but is closed at its upper end. This closure at the upper end merges into a head 5 provided with an over-hanging portion 6 of greater dimension than the over all dimension of the threads 2. This head is also provided with a screw slot 7 to facilitate insertion and removal of the plug.

It will be apparent from the consideration

of the above described plug that the opening, which is also threaded, is engaged by the threads 2 on the annulus 1 and the plug thus drawn into the opening until the head 5 makes tight contact with the edges thereof. In the event of moisture entering the plug the various parts of the plug will swell. An inspection of the drawing will show, however, that swelling of the head part 5 will merely cause this part to extend itself over the surface of the shell. Expansion of the neck piece 4 will be ineffective to cause binding between this part and the shell opening due to the smaller diameter of the neck 4 resulting from the inset at shoulder 3. Expansion of the annulus 1 would cause binding but this annulus is made so thin that the expansion is not only materially reduced but also the compression which may be exerted to cause binding is greatly reduced. Due to this construction there will be no appreciable binding between the annulus 1 and the shell opening. It will be apparent from the above that my plug will not bind appreciably upon exposure to moisture.

Referring to Figures 3, 4, and 5, for a description of the second form of plug, 11 represents a cylindrical body provided with a recess 12 of rectangular cross-section extending diametrically therethrough. Extending through this recess 12 is a rod 13 provided on its ends with screw threads 14 and so arranged that its grain is parallel to the axis of the opening 12. At its upper end the body 11 expands at shoulders 15 to form a head 16 of greater diameter than threads 14. This head 16 is also provided with a slot 17 to facilitate the insertion and withdrawal of the plug.

A consideration of the above description will show that this plug is secured in the opening by means of the rod 13 through the engagement of the threads 14 thereon with corresponding threads in the shell opening. The plug is screwed into the opening until the head 16 seats firmly on the surface of the shell and thus closes the opening. Should the plug now be moistened, inspection of the drawing will show that the resulting swelling of head 16 will merely cause it to extend over the surface of the shell and the resultant expansion of body 11 will be ineffective to cause binding because of the reduced diameter of the body which pre-

vents it from coming in contact with the walls of the opening. It is well known that moisture does not expand wood appreciably along the grain and accordingly there will be no expansion of the rod 13. It will be apparent from the above that the entrance of moisture into this plug will not cause binding of the plug.

In the two forms of plugs shown above I have provided plugs wherein the entrance of moisture will not cause appreciable binding. It will be apparent that I may use means to secure the plug in the shell other than a continuous screw thread, such for example as a segmental thread or a bayonet slot construction. Whatever method of securing is employed my construction will operate with equal efficiency to properly close the opening without causing binding. I also realize that other materials than wood may be used for part or all of either plug. It will be apparent that where such material possesses the same properties of expansion by acquisition of moisture, my invention will be applicable throughout to this material. Where such material is substituted for a part of the plug other than that which functions to secure the plug to the shell, it will be apparent that such substitution does not in any way differentiate from the essential elements of my plug. It will also be apparent that in the construction shown by Figures 1 and 2 the opening is closed by both the body of the plug and the head thereof. I realize that this duplication of closures

may be found unnecessary and one dispensed with. In the construction shown in Figures 3, 4, and 5, the body does not completely close the opening, yet for many purposes it closes it to a sufficient degree. Accordingly this construction also provides a duplication of closures and again I realize that one may well be omitted. Further, in the construction shown in Figures 3, 4, and 5 I realize that a plurality of rods may be substituted for the one rod. Also these changes and modifications I consider to be within the scope of my invention. I also realize that my plug is not limited to use in shells and I do not consider my invention in any way limited to that use. I also consider as within the scope of my invention all modifications included within the scope of the appended claim.

I claim:—

A cylindrical plug for shrapnel shells comprising a body of wood having one portion of an external diameter greater than that of the hole to be plugged, a threaded portion for retaining said plug in said hole, said body having a cavity formed in one end extending into said body beyond said threaded portion, and a portion of lesser diameter than said hole and said screw threaded portion, arranged between said threaded portion and said portion of greater diameter than said hole.

In testimony whereof I affix my signature.

MATTHEW E. DUNLAP.
